UNITED STATES PATENT OFFICE.

JOSEPH S. DUNCAN, OF CHICAGO, ILLINOIS, ASSIGNOR TO
ADDRESSOGRAPH COMPANY, OF CHICAGO, ILLINOIS, A
CORPORATION OF ILLINOIS.

TYPE-SETTING MACHINE.

No. 811,623.

Specification of Letters Patent.

Patented Feb. 6, 1906.

Application filed May 23, 1904. Serial No. 209,368.

To all whom it may concern:

Be it known that I, JOSEPH S. DUNCAN, a citizen of the United States, residing at Chicago, in the county of Cook and State of Illinois, have invented new and useful Improvements in Type-Setting Machines, of which the following is a specification.

The primary object of this invention is to provide a machine adapted to be easily and rapidly operated to take types from a supply and set them in a suitable holder.

The invention has relation more particularly to a machine for setting rubber type in holders; and its object is to provide a machine of simple construction which can be quickly operated by unskilled labor to set up addresses or other subject-matter in holders which are used in addressing or other printing machines.

20 The invention also has for its object to provide for introducing slugs or blank type into the holder at the ends of the lines to hold the type solidly together and in fixed upright position in the type-grooves.

25 The invention has other objects in view which will be fully disclosed in the detailed description of one embodiment of the machine which I have chosen as illustrative of the invention.

30 In the accompanying drawings, Figure 1 is a plan view, partly broken away. Fig. 2 is a sectional view on the line 2 2 of Fig. 1. Fig. 3 is a sectional view on the line 3 3 of Fig. 1. Figs. 4 and 5 are sectional views corresponding, substantially, to Fig. 2 and showing the setter in two positions. Fig. 6 is a detail view of a portion of the carriage, partly in section, with the holder and holder-frame removed. Fig. 7 is a sectional view on the line 7 7 of Fig. 6. Figs. 8 and 9 are plan views showing the devices for adjusting the type-holder frame in two positions. Figs. 10 and 11 are sectional views showing the slug-plugger devices in the two positions. Fig. 12 is a 45 detail sectional view of the slug-plugger. Fig. 13 is a detail sectional view on the line 13 13 of Fig. 11.

The machine comprises a frame which in the drawings is shown to consist of the sides 50 1, connected together by the bed or plate 2, the grooved bar 3, the front bar 4, and the

rod 5. The bed is preferably pitched at an angle, as shown in Fig. 2, and the type 6 are arranged in the channels 7 on the bed. These channels may be formed in the bed itself, or 55 they can be formed by bending metal sheets into proper shape to receive the type, and I preferably arrange across the channels an index-plate 8, bearing characters corresponding to those on the type. 60

The machine illustrated in the drawings is designed especially for setting rubber type in a holder 9, Fig. 1, which is provided with three type-grooves 10, and this holder is carried by a frame which is adjustably mounted 65 on a carriage adapted to be moved back and forth to register the holder-groove, in which type are being set, with the different channels. The carriage comprises a frame 11 with grooved rollers 12 to travel on the rod 5 and 70 a roller 13 to travel in a guideway or track 14 in the plate 3, Figs. 1, 2. A setter-arm 15 is pivotally connected at its lower end to a link 16, which is pivoted to the carriage-frame at 18, and a spring 19 is fastened at 20 75 to said arm and to a lug 21 on the carriage-frame to hold the setter-arm normally in the position illustrated in Fig. 2. The setter-arm carries at its upper end a blade 22, which is adapted to enter between the first and second type in a channel and move the first type, in a manner hereinafter described, from its channel into a groove in the holder 9. The type-setter comprising the arm and blade is operated by depressing a key 23 on 80 the lever 24, which is pivoted at 25 to a rearward extension 26 of the carriage-frame and is connected by a link 27 to an arm 28, pivoted at 29 on the carriage-frame, Figs. 2, 7. The arm 28 carries a roller 30, which works 90 in a socket 31 in an arm 32, pivoted at 33 on the setter-arm, and this arm 32 has a finger 34, which projects forward above the pivot 30 toward the pivot 29. A flat spring 35 bears on the finger 34 and holds the arm 32 95 in operative position. The arms 28 and 32 operate like a toggle, the one being pivoted to the carriage-frame at 29 and the other being pivoted to the setter-arm at 33, and in their normal position they extend at an angle 100 to each other, as shown in Figs. 2 and 7. When the key is depressed, the link 27 pulls

the arm 28 down and the roller 30 working in the socket 31 (the spring 35 constantly pressing on the finger 34) moves the arm 32 and the setter-arm laterally to the position shown in Fig. 4. At this time the shoulder 36 on the setter has been carried from the position shown in Fig. 2 under and in engagement with the hooked end of an arm 37 on the key-lever, as shown in Figs. 4 and 5, and on the further depression of the key the setter is moved downward through the medium of the arm 37 from the position shown in Fig. 4 to the position shown in Fig. 5, and the type is thereby carried from the channel into the holder. The spring 19 returns the parts to their normal position, Fig. 2, when the key is released, a stop 81 on the carriage limiting the upward movement of the setter-arm. The depression of the key is a continuous movement and not interrupted, and during such depression the blade of the setter is caused to move in two directions at right angles to each other, first laterally into the type-channel and then downward lengthwise of the channel.

A plate 42, fast to a projection 38 on the setter-arm, is provided with a lug 39, which is arranged to engage and slide down on the upper face of a guide-lug 40 on the carriage-frame, Figs. 6, 7, when the setter is moving from the position shown in Fig. 2 to the position shown in Fig. 4. When the setter-arm is moving downward from the position shown in Fig. 4 to the position shown in Fig. 5, the lug 39 moves downward behind the guide-lug 40, and when the spring 19 returns the setter-arm to its normal position the upper edge of the lug 39 slides up over the inclined lower face of the lug 40 and up in front of said lug to the position shown in Fig. 6. The setter-arm is therefore guided in its movements by the lug 39 traveling in engagement with the guide-lug 40, and this insures the correct movements of the several parts.

The type in each channel are normally held in place in the channel by a spring-arm 41, which is fastened at one end to the bed and has its other end arranged to close the lower end of the channel, Figs. 2, 5; but when the setter-blade moves into the channel, Fig. 4, the upper end of plate 42, which may be formed into a figure 42, engages an arm 43 on the spring 41 and moves the spring away from the channel, as shown in Fig. 4, so as not to obstruct the movement of the type when the setter-blade carries the type into the holder.

To prevent the second and following type in the channel from sliding out of a channel behind the setter-blade when the latter moves the first type into the holder, I provide the carriage with a spring-arm 80, which is engaged by the arm 15 and pressed against one or more of the type back of the first type at the time that the setter-blade enters the chan-

nel, Fig. 4. The arm 80 thus holds the second and following type in position in the channel until the setter-arm has carried the first type down into the holder, and at or about this time the plate 42 is released from engagement with arm 43 and the spring 41 returns to its position against the discharge end of the channel.

To register the type-groove properly with the channel from which it is desired to move the type, I provide the front bar 4 with a number of teeth 44, leaving sufficient space between them to receive the key-lever. When the carriage has been properly adjusted to bring the type-groove into register with the type-channel and the key is depressed, the lever will enter between a pair of teeth and lock the carriage in place during the setting operation and until the key-lever is withdrawn from between the teeth by the spring 19.

The holder is clamped in rigid position against the lugs 45, Fig. 8, on the holder-frame 46 by the lever 47, Fig. 1, and this frame is mounted to be adjusted laterally on the guide-rods 48 on the carriage-frame. The holder-frame illustrated is constructed to receive a holder with three type-grooves, as shown, and a spring 49, Figs. 8, 9, is arranged to pull the holder from its initial position at the left to its final position at the right of the carriage-frame. After the holder has been secured in place in the holder-frame the frame is moved to the extreme left and the dog 50, carried by the lever 51, pivoted to the carriage-frame at 52, will enter the middle groove in the holder to hold the frame against the tension of the spring 49 with the first groove of the holder in alignment with the setter-blade. When it is desired to start a new line of type, the lever 51 is depressed to withdraw the dog 50 from the type-groove, and at the same time a dog 53, carried by a lever 54, pivoted at 55 on the carriage-frame, is caused to engage the holder by the pin 56 bearing on said lever 54 to limit the movement of the holder-frame under the influence of spring 49. Then the pressure on lever 51 is released and the spring 57 will swing the lever 54 to carry dog 53 out of engagement with the holder, and as lever 54 engages pin 56 and swings lever 51 the dog 50 will be carried down into the next groove of the holder, or if type are to be set in the last groove of the holder the dog 50 will engage a lug 58 on the carriage-frame. In Fig. 3 the holder is shown in position for receiving type in the middle groove, and Figs. 8 and 9 illustrate two steps in the feeding operation of the holder-frame to carry the holder from the position shown in Fig. 3 to position, Fig. 9, for receiving type in the third or last groove.

To hold the type securely in place in the holder, I provide means for inserting slugs as required at one or both ends of each line of

type, and these slugs are somewhat larger in diameter than the type-groove, so that they will be held securely in fixed position in the groove by frictional engagement with the side walls thereof after being forced into place as hereinafter described. At one end of the machine I provide a frame 60, Fig. 1, which comprises the guide-rods 61 61'. The slug-setter is mounted to travel on these rods 61 61' in a direction substantially at right angles to the direction of travel of the carriage 11. This slug-setter comprises a carriage 62, on which is mounted a slug-channel 63, substantially like the type-channel 7. A pusher 64 is arranged in this channel and connected to a coil-spring 65, mounted on a fixed stud 66 on the carriage 62, the object of the pusher being to constantly push the slugs in the channel toward the front end thereof with the first slug beneath the driver. The slug-driver 67, Figs. 10 to 12, is connected by a pin 68 with a lever 69, which is pivoted to a sleeve 70' on the rod 61', and this driver is arranged to operate within a housing 71 and is normally held in elevated position by a spring 72. The slug-setter carriage 62 is pivotally mounted on the rods 61 and at its outer end is provided with upturned lugs 73, which are grooved to receive the rod 61', and a spring 74, connected to the outer end of the carriage 62 and to a lug 75 on the sleeve 70', holds the outer end of the carriage normally up in engagement with the rod 61', as shown in Fig. 10. The forward end of the slug-channel 63 is closed, Fig. 13, and the channel is provided on its bottom at said end with a funnel-shaped or contracted discharge-opening, through which the first slug is forced by the driver into a groove in the holder. When it is desired to insert a slug in one of the type-grooves, the holder-carriage is moved to the extreme right until the roller 12 engages the side of the machine, and then the slug-setter carriage is moved (from its normal position, Fig. 2) on the rods 61 61' until the discharge of the slug-channel is located directly opposite the place in the type-groove which the slug is to occupy, Fig. 10. The discharge of the type-channel constitutes, in effect, the end of the channel, although it is at right angles to the channel, and it is formed by two inclined short sides 76, which are adapted to rest upon the side walls of the type-groove when the slug is being driven into the groove, Fig. 13, and two long sides 77, which enter the type-groove, Fig. 12, these four sides being contracted at their outer edges to such an extent that the slugs will be compressed while being driven therethrough into the type-groove. In this way I provide for easily and quickly setting a slug of larger size than the type and larger in diameter than the width of the type-groove in proper position in the type-groove. The slug is sufficiently compressed in passing through the discharge of the slug-channel to permit of its slipping easily into place in the type-groove, and it then expands and is secured in fixed position in the type-groove by frictional engagement with the side walls thereof to hold the slug rigidly in place and prevent them from spreading or moving in the type-groove. After the discharge of the slug-channel has been arranged in proper relation to the type-groove the lever 69 is depressed, and the spring 74 being weaker than the spring 72 the entire slug-setter carriage will be depressed from the position shown in Fig. 10 to the position shown in Fig. 11 until the discharge end of the slug-channel rests against the holder, as shown in Fig. 13. The slug-setter carriage having thus reached the limit of its movement, continued pressure on the lever 69 will operate the driver 67 to force the slug at the end of the slug-channel into the type-groove. When the pressure on the lever 69 is released, the springs 72 and 74 will return the parts to their normal position. It will be observed that the slug can be set in any desired position in the type-groove, because the holder-carriage is adjusted to bring the groove in alinement with the discharge of the slug-channel, and the slug-setter carriage is adjusted to move said discharge to any position lengthwise of the type-groove. The pusher always keeps the first slug in the channel in proper position beneath the driver, so that it is only required to position the discharge and then operate the driver to set the slug in the type-groove.

The general operation of the machine will be readily understood from the foregoing detailed description of the construction and arrangement of the several parts and groups of mechanism. A holder of suitable construction, and I do not restrict myself to any particular kind, is clamped in place in the holder-frame and the latter is moved to the extreme left, so that the first type-groove will aline with the setter-blade, the dog 50 entering the second type-groove and holding the frame in fixed position. The holder-carriage is then moved by means of the key 23 until the setter-blade is above the channel containing the type which it is desired to set into the groove, and thereupon the key-lever is depressed into the socket between the teeth 44, which locks the carriage in proper relation to said type-channel. At or about the same time that the carriage is locked, as just stated, the setter-blade begins its movement to enter the type-channel between the first and second type thereof and to move the first type from the channel into the type-groove. At or about the same time the setter-blade enters the type-channel the spring-arm 41, which holds the type normally in position in the channel, is depressed, so that the setter-blade can immediately move the type into the type-groove of the holder. This operation is re-

peated until the line of type is completed, and then slugs can be inserted at one or both ends of the line of type, as may be desired. This is accomplished by moving the carriage-frame to the extreme right to carry the type-groove into alignment with the slug-driver and then adjusting the slug-driver carriage until the slug-discharge is properly positioned relative to the type-groove and the place the slug is to occupy. Then the lever 69 is depressed and the slug is driven into place in the type-groove. It will be observed that when the holder-carriage is moved to the extreme right for the slug-setting operation the type-groove in which the type has just been set, whether it be the first, second, or third groove, will be properly aligned with the slug-discharge, because the holder is adjusted with relation to the fixed setter-blade and the latter bears a fixed relation to the carriage, so that when the roller 12 engages the right side of the machine-frame whichever groove is in alignment with the setter-blade will be properly positioned beneath the slug-discharge.

The machine which I have illustrated and described as one embodiment of the invention is designed for setting up addresses with rubber type in holders for addressing-machines; but it will be readily understood that the invention is not in any respect confined to the particular kind of type or holder or to the subject-matter of the form which is set up. The operation of the machine is very simple, as the operator is only required to set up a type in a type-groove, to move the holder-carriage until the setter-blade is in proper operative relation to the type-channel containing the type which it is desired to set up, and then operate the key. The depression of the key locks the carriage and operates the setter and a spring returns the parts to their normal position.

I do not restrict the invention to the particular construction and arrangement of parts herein shown and described, but reserve the right to make all such changes in the form, construction, and proportion of parts which fairly come within the spirit and scope of the invention. The type-channels may be of any suitable character for holding type and the setter-blade may be any suitable device adapted to enter between two type and move one or more as desired from the channel into the holder. The holder is carried close to the discharge end of the type-channels, so that the type may readily slide from a channel into a type-groove.

I prefer to employ a setter-blade 22, so that it will readily enter between two type, and this blade is formed on or attached to an arm 22', which is adjustably secured on the arm 15. The key-lever forms a handle for the carriage, by means of which it can be moved back and forth, and the operator is

thus required to operate a single lever for adjusting the carriage and operating the setting means.

Without limiting myself to the exact construction and arrangement of parts herein shown and described, what I claim, and desire to secure by Letters Patent, is—

1. In a type-setting machine, the combination with a series of type-channels, of a carriage adapted to travel adjacent to said channels, a type-holder on the carriage, setting means carried by the carriage for moving type from the channels into the holder, a key-lever for operating said setting means and forming a handle for moving said carriage, and means for locking the key-lever and through the key-lever locking the carriage during the setting operation.

2. In a type-setting machine, the combination with a series of type-channels, of a carriage, a type-holder on the carriage, setting means on the carriage for moving type from the channels into the holder, means for locking the carriage, and a lever adapted to be operated first to move the carriage into operative relation to a type-channel and then to engage the locking means to lock the carriage and operate the setting means.

3. In a type-setting machine, the combination with a series of type-channels, of a carriage, a type-holder on the carriage, setting means for moving type from the channels into the holder, a bar provided with teeth, and a lever for operating the setting means adapted to be engaged with said toothed bar to lock the carriage during the setting operation.

4. In a type-setting machine, the combination with a series of type-channels, of a carriage, a type-holder on the carriage, setting means for moving type from the channels into the holder, a bar provided with teeth forming sockets therebetween corresponding in relation to the type-channels, and a lever for operating the setting means adapted to enter one of said sockets to lock the carriage during the setting operation.

5. In a type-setting machine, the combination with a series of type-channels, of a bar located opposite the discharge end of the channels and having sockets corresponding in relation to the type-channels, a movable carriage arranged to travel between the type-channels and said bar, a type-holder on said carriage, setting means on the carriage for moving type from the channels into the holder, and a lever arranged to enter one of said sockets to lock the carriage during the setting operation.

6. In a type-setting machine, the combination with a series of type-channels, of a bar located opposite the discharge end of the channels and provided with teeth forming sockets in parallelism with the type-channels, a movable carriage arranged to travel between the

type-channels and said bar, a type-holder on the carriage, a setter device on the carriage for moving type from the channels into the holder, and a lever connected to said carriage 5 and setter for moving the carriage and then operating the setter and adapted to enter one of said sockets to lock the carriage during the setting operation.

7. In a type-setting machine, the combination with a series of type-channels, of a carriage, a type-holder on the carriage provided with one or more type-grooves, and setting means arranged to first move into one of the type-channels and then move the first type in 15 said channel into a type-groove.

8. In a type-setting machine, the combination with a series of type-channels, of a type-holder, a carriage, a setter-blade on the carriage and means for operating said blade to 20 first enter a channel between the first and second type therein and then move the first type from the channel into the holder.

9. In a type-setting machine, the combination with a series of type-channels, of a type-holder, a setter device moving in a rectangular orbit for moving the type from a channel 25 into the holder, and means for operating said setter.

10. In a type-setting machine, the combination with a series of type-channels, of a carriage, a type-holder on the carriage, a setter device, an arm on the carriage carrying said setter, and means for operating said arm to cause said setter to travel in a rectangular 35 orbit and move the type from a channel into the holder.

11. In a type-setting machine, the combination with a series of type-channels, of a carriage, a holder on the carriage, a setter device, 40 means for moving said setter in an angular orbit to enter and move a type from a channel into the holder, and guiding means for the setter.

12. In a type-setting machine, the combination with a series of type-channels, of a carriage, a type-holder on the carriage, a setter device, an arm on the carriage carrying said setter, means for operating said arm, and guiding means for the arm to cause the setter 50 to travel in a rectangular orbit and move the type from the channel into the holder.

13. In a type-setting machine, the combination with a series of type-channels, of a carriage, a type-holder on the carriage, a setter, 55 an arm on the carriage carrying said setter, a key-lever for operating said setter-arm, a guide-lug on the carriage, and a lug on the setter-arm guided on said guide-lug to guide the setter-arm and setter.

14. In a type-setting machine, the combination with a series of type-channels, of a carriage, a type-holder, a setter device for moving type from the channels into the holder, and means for operating said setter comprising 65 an arm carrying the setter, a key-lever,

and a toggle connection between the setter-arm and key-lever.

15. In a type-setting machine, the combination with a series of type-channels, of a carriage, a type-holder on the carriage, a setter device, an arm on the carriage carrying said setter device, a key-lever, and an arm on the key-lever for engaging the setter-arm to cause the setter to move type from the channels into the holder. 70

16. In a type-setting machine, the combination with a series of type-channels, of a carriage, a type-holder on the carriage, a setter device, an arm on the carriage carrying said setter, a key-lever, a toggle connection between the setter-arm and the key-lever to cause the setter to move into a type-channel, and an arm on the key-lever to move the setter-arm and cause the setter to move the type from the channels into the holder. 75

17. In a type-setting machine, the combination with a series of type-channels, of a carriage, a type-holder, a setter device for moving type from the channels into the holder, an arm carrying said setter, a key-lever, a socket pivoted on the setter-arm, an arm 28 pivoted on the carriage, a roller on said arm 28 working in said socket-arm, a link connecting the key-lever with the arm 28, and an arm 37 to engage the setter-arm. 80

18. In a type-setting machine, the combination with a series of type-channels, of a type-holder, a setter device for moving the type from the channels into the holder, means for holding the type in the channels, and means 100 for moving said holding means from the channel in which the setter is operated.

19. In a type-setting machine, the combination with a series of type-channels, of a type-holder, a setter device for moving type from the channels into the holder, an arm carrying said setter, a spring-arm on the machine for closing the discharge end of each channel, and means on the setter-arm for moving said spring-arm away from the channel when the 105 setter moves therein.

20. In a type-setting machine, the combination with a series of type-channels, of a carriage, a type-holder on the carriage, a setter-blade on the carriage, and a key-lever connected to the blade and adapted to be depressed to cause the setter-blade to first enter a type-channel and then move the type into the holder. 110

21. In a type-setting machine, the combination with a series of type-channels, of a carriage, a type-holder on the carriage provided with one or more type-grooves, a setter device carried by the carriage for moving type from the channels into the holder, and means 115 for adjusting the type-holder relative to said setter device.

22. In a type-setting machine, the combination with a series of type-channels, of a carriage, a type-holder on the carriage, a setter 130

- blade on the carriage, means for adjusting the holder relative to said blade, and means for operating said blade to move type from the channels into the holder.
- 5 23. In a type-setting machine, the combination with a series of type-channels, of a carriage, a type-holder, a movable frame on the carriage carrying said type-holder, a setter-device for moving type from the channels 10 into the holder, and means for adjusting said frame on the carriage relative to said setter.
- 15 24. In a type-setting machine, the combination with a series of type-channels, of a carriage, a movable frame on the carriage, a type-holder carried by said frame, a setter device for moving type from the channels 20 into said holder, and feed-dogs for adjusting said frame and holder on the carriage relative to the setter.
- 25 25. In a type-setting machine, the combination with a series of type-channels, of a carriage, a movable frame on the carriage, a type-holder carried by said frame, a setter device for moving type from the channels 30 into said holder, a spring-actuated dog 53, and a lever 51 carrying a feed-dog and adapted to be operated to operate the feed-dog 53 to adjust the holder relative to the setter.
- 35 26. In a type-setting machine, the combination of a holder provided with a type-groove open at the top, and slug-setting means comprising a driver operating at a right angle to the groove to set a slug into the groove through its top.
- 40 27. In a type-setting machine, the combination of a holder provided with a type-groove open at the top, and slug-setting means comprising a driver arranged to operate above the top of a slug to set the slug into said groove through the top thereof.
- 45 28. In a type-setting machine, the combination of a holder provided with a type-groove open at the top, and slug-setting means movable lengthwise of the groove for setting slugs therein at any point along the groove.
- 50 29. In a type-setting machine, the combination of a holder provided with a type-groove open at the top, and slug-setting means arranged to operate above the holder and movable lengthwise of the groove for setting slugs into the groove through its top and at any point along the groove.
- 55 30. In a type-setting machine, the combination of a holder provided with a type-groove open at the top, a slug having its base wider than the open top of the groove, and means for setting said slug in the groove.
- 60 31. In a type-setting machine, the combination of a holder provided with a type-groove open at the top, a slug having its base wider than the open top of the groove, and means for setting said slug in the groove through the top thereof and at any point along the groove.
- 65 32. In a type-setting machine, the combination with means for setting type in a holder, of means for setting slugs capable of being compressed, said means comprising a contracted discharge, and a driver for moving the slugs through the discharge into the holder.
- 70 33. In a type-setting machine, the combination with means for setting type in a holder, of means for setting compressible slugs in the holder comprising a slug-channel, having a contracted discharge, means for moving said discharge into engagement with the holder, and a driver for moving the first slug in the channel through the discharge into the holder.
- 75 34. In a type-setting machine, the combination with means for setting type in a holder, of means for setting slugs in the holder comprising a discharge arranged to engage the holder and enter the type-groove 80 therein, a driver, and means for operating said driver to force a slug through the discharge into the type-groove.
- 85 35. In a type-setting machine, the combination with means for setting type in a holder, of slug-setting means comprising a slug-supply, a discharge, means for adjusting the discharge relative to the holder, and means for moving a slug from the supply into the holder.
- 90 36. In a type-setting machine, the combination with means for setting type in a holder, of slug-setting means comprising a slug-supply, a discharge, a flexible frame carrying the discharge, means for moving said discharge into engagement with the holder and a driver for moving a slug through the discharge into the holder.
- 95 37. In a type-setting machine, the combination with a movable carriage, of a type-holder carried thereby, and a slug-setter, said carriage being adapted to carry the type-holder into operative position with relation to the slug-setter and said slug-setter being movable at right angles to the direction of movement of the carriage.
- 100 38. In a type-setting machine, the combination with a type-holder, of a slug-setter comprising a discharge, a driver, a lever connected to said discharge and driver and adapted to move the discharge into engagement with the holder and then operate the driver to move a slug into the holder.
- 105 39. In a type-setting machine, the combination with a type-channel, of a type-holder having a type-groove, setting means for moving the first type from the channel into the groove, and means operated by the setting means to bear against the face of the second type to hold the remaining type in place in the channel while the first type is being moved from the channel into the type-groove.
- 110 40. In a type-setting machine, the combi-

nation with a type-channel, of a type-holder having a type-groove, setting means for moving type from the channel into the groove, a spring-arm, and an arm operated by the 5 setting means for pressing the spring-arm against the face of the second type to hold the remaining type in the channel while the

first type is being moved from the channel into the groove.

JOSEPH S. DUNCAN.
